UNITED STATES PATENT OFFICE.

ELSA BOYANCE AND MARIE PEKÁRY, OF NEW YORK, N. Y.

SANITARY STREET CLEANER.

Application filed February 10, 1925. Serial No. 8,253.

This invention relates to street cleaners, and while we shall hereinafter refer to our device as a street cleaner it is to be clearly understood that the device may be used for 5 many other purposes, and we do not limit ourselves to any particular use.

An object of the invention is to provide a wheeled receptacle, manually moved over the street or other surface, and causing a rotary brush to revolve to thoroughly clean the street or other surface and carry the articles or particles collected into the receptacle without raising any appreciable amount of dust, and collecting the dirt and 15 trash, which can be dumped or emptied from time to time, as may be desired.

Our invention is designed primarily as a labor saving device, which only needs to be rolled over the surface to be cleaned, and 20 its brush will automatically revolve so as to thoroughly clean the surface and collect the dirt within the receptacle or receptacles forming a portion of the apparatus.

With an apparatus or device of this character much fewer men will be needed to 25 clean the streets or any given surface, the manual labor will be reduced, a greater efficiency had, and the nuisance and danger due to the flying dust will be overcome.

With these and other objects in view, the invention consists in certain novel features of construction and combinations and arrangements of parts, which will be more 30 fully hereinafter described and pointed out in the claims.

In the accompanying drawing—

Figure 1 is a view in side elevation illustrating my improved street cleaner;

Figure 2 is a view in longitudinal section through the center of the device;

Figure 3 is a top plan view;

Figure 4 is a fragmentary view in cross section on the line 4—4 of Figure 2; and

Figure 5 is a fragmentary view in cross 45 section on the line 5—5 of Figure 2.

1 represents the body or receptacle of our improved sanitary street cleaner, which is of box-like form and which is made preferably of metal, although of course the invention is not limited to the materials employed.

In the receptacle 1 and secured to the bottom thereof are bearing brackets 2 through which axles 3 project and are supported in 50 wheels 4 mounted to run on the ground. These wheels 4 have rubber or other analog-

ous tires 5, not only to cushion the wheels but also to provide resilient friction surfaces to drive our improved rotary brush 6, as will be hereinafter explained.

On the outer faces of the sides of the body or receptacle 1, brackets 7 are secured and constitute bearings for a rod 8 which is secured in place by nuts 9 screwed onto the ends thereof. This rod 8 provides rotary 65 mounting for the brush 6 and the latter is preferably made with a hollow cylindrical core 9 having perforated disk-like ends 10 receiving the rod 8 and turning freely thereon. The sides of the body 1 are recessed, 70 as shown at 11, to accommodate the cylindrical core 9, as clearly shown in Figures 1 and 2, the upper end of the recess being semicircular.

The brackets include upper plate portions 75 which are permanently secured on the outer surface of the sides of receptacle at the top of the recess 11, outwardly offset hanger arms having perforations at their lower ends through which rod 8 is passed, and inwardly 80 extending curved flanges, the shape and curvature of these flanges coinciding with those of the recesses 11, so that these flanges fit snugly within these side recesses and form a protector and reinforce for the edges 85 of the side openings, as well as a housing or hood for the outer ends of the cylindrical core 9, with which it is also concentric.

By this construction and arrangement of parts the brush is held snugly and accurately 90 in place, the edges of the side openings are protected and strengthened and there is practically no space left at the sides between the brush and the receptacle as the projecting ends of the core 9 fit into the flange. 95 Also by the above arrangement the brushes may be quickly removed by simply removing the rod 8 from the core 9, whereupon the brush will drop freely out of the side recesses. The brush may be as readily re- 100 placed by reversing these operations.

The bristles of the brush 6 are preferably arranged in groups and spaced apart and located with the desired relationship to each other so as to effectually operate to clean 105 the surface and take up the dirt and trash. The bristles of the brush are to be made of such material that they will be relatively rigid although they will have the necessary resiliency to allow the desired bending action as they function in their cleaning 110 operation.

The bottom 12 of the body or receptacle 1 is open at its intermediate portion to accommodate the brush 6, and adjacent said brush arcuate guard plates 13 and 14 are 5 secured to the bottom. One of these arcuate plates has a downwardly projecting shovel-like lip 15 over which the dirt and particles are directed by the brush until they reach the upper portion of the body 1, when they 10 fall into the body onto the bottom and are deposited thereon.

It is of course necessary to provide means for allowing the accumulation of dirt and trash to be discharged or removed from the 15 receptacle, and with this idea in view we provide doors 16 at the ends of the body which are hingedly connected as shown at 19, and have suitable catches 20 to hold them in closed position. When these doors are 20 swung to open position it is obvious the accumulation in the body can be removed.

While we have illustrated the doors at one particular point of the body, it is obvious that they may be located at any desired place in accordance with the desire of 25 the trade.

Handle bars 21 are secured to the body, are strengthened by brace rods 22, and have a handhold 23 at their free ends to allow 30 the operator to grasp the same and move the device over the ground or the surface.

In order that rotary motion may be transmitted to the brush, it will be noted that the 35 tires 5 of the wheels 4 directly engage the end portions of the cylindrical core 9 of brush 6. Hence, when the device is moved over the ground the turning movement of the wheels will impart a positive rotary motion to the brush so as to cause the latter to sweep the ground with such force 40 and cleaning action as to thoroughly clean the surface and pick up the dirt and other particles or articles and deposit them in the receptacle.

An apparatus of this kind will dispense 45 with a large number of men, such as are now necessary to clean the streets, will make the work much easier for those employed, will most efficiently perform the functions for which it is intended, and will in a very real 50 sense constitute a sanitary manner of cleaning as the dust will not fly and disease germs will not be scattered as they are under present conditions.

While, as above stated, the device is especially adapted for use as a street cleaner 55 it is capable of many efficient uses. It is well adapted for removing leaves in the fall, for cleaning up walks and driveways, and hence we desire to cover the apparatus 60 for any use to which it can be put.

Various slight changes and alterations 65 might be made in the general form of the parts described without departing from our invention, and hence we do not limit ourselves to the precise details set forth but consider ourselves at liberty to make such slight changes and alterations as fairly fall 70 within the spirit and scope of the appended claim.

We claim:

A street cleaner comprising a body having aligned recesses in its opposite sides extending upwardly from the lower edges of the sides and having curved upper ends, 75 brackets on said sides adjacent the recesses having perforated arms extending over the recesses, and inwardly extending protecting flanges curved to fit the upper ends of said recesses, said body having a transverse opening through its bottom, a removable rod extending through said perforated arms, a brush rotatably mounted on said rod and extending through said opening, and means 80 to rotate said brush.

ELSA BOYANCE.
MARIE PEKARY.
